COLLAR

Simon Touloumis, Long Island City, N. Y.

Application September 17, 1934, Serial No. 744,377

3 Claims. (Cl. 2—140)

This invention relates to collars and has for an object an improved wing-type collar which conceals that portion of the tie which passes around the collar and prevents the tie from creeping up the collar, and which is so constructed as to be easily laundered by use of the standard laundry appliances.

A collar embodying the invention consists of inner and outer multi-ply members of approximately the same length which are stitched together at the top edge only in the manner customary with turn-down collars. Each end of the inner member terminates in a tapering portion provided with a button-hole and the ends of the outer member terminate in portions which fold back to form wings. A locking member is stitched to each outer member in register therewith and has a portion overlapping the inner face of the inner member. The locking member ends have button-holes in register with the inner member button-holes and the collar-button passes through all of the button-holes.

This collar can be easily laundered by use of the standard laundry appliances in the same manner as a turn-down collar is now laundered. When the collar is worn, the locking members hold the ends of the outer member tight against the inner member and give the collar the appearance of a standard wing collar.

Other objects, novel features and advantages of this invention will become apparent from the following specification and accompanying drawing, wherein:

Fig. 1 is a perspective view of a collar embodying the invention in the position it assumes when being worn.

Fig. 2 is a perspective view of the collar in the position which it assumes when resting normally on a flat support, with the locking member in inoperative position.

Fig. 3 is a partial perspective view with the locking member in operative position.

Fig. 4 is a section on the line 4—4 of Fig. 1, and

Fig. 5 is a flat view of the collar as it appears after having been passed through a mangle for ironing.

The collar comprises a two-ply inner member 10 and a two-ply outer member 11, both of which plies are stitched together in the usual manner and the two members 10 and 11 are stitched together along the edge 12 in the same manner as standard turn-down collars. The members 10 and 11 also bear some relation to each other regarding size, shape and cut as do the corresponding parts of a standard turn-down collar. The

ends of the inner member 10 are tapered as at 13 and terminate in button-hole portions 14 provided with the usual button-holes 15. The outer member 11 terminates in wing portions 16 which are folded along a line 17 which is in substantial registration with the tapering edge 13 of the inner member. The bottom edge of the outer member is made obliquely at both ends along lines 18 to be in substantial registration with the bottom edge of the wing 16. To each wing is attached a two-ply locking member 19 which comprises a triangular portion 19a which registers with the wing 16 and has a curved edge portion 19b which overlies the inner face of the inner member 13. The composite collar wing is thus of four-ply, while the overlapping portion is two-ply. The locking portion is provided with button-holes 20 which register with the button-holes 15.

When the collar is worn, the tie is arranged between the inner and outer members and is generally concealed and held against upward movement. The locking portions overlie the ends of the inner member and by reason of being attached to the button-hole, these members keep the inner and outer portions of the collar in close relation so that the collar has the same appearance as a standard wing-collar.

The collar above described can be easily laundered according to a standard laundry practice with standard laundry appliances. As shown in Fig. 5, the collar may be turned out flat for washing purposes and in such position may be run through the standard mangle in the usual way. The curved portion of the locking member will be pressed against the inner face of the outer member but the wing is completely exposed on both sides and will be properly ironed. After the collar has been discharged from the mangle, the two members may be turned against each other and the collar rolled in the standard manner for turn-down collars and the wings swung back in the standard manner for wing collars. These collars may be produced at substantially the same labor and material cost as standard turn-down collars but when finished have the appearance of a wing collar and the advantages of a turn-down collar respecting concealment of the tie and holding of it against creeping.

The triangular portion 19a of the locking member 19 is stitched to the wing 16 along the edges thereof and along the fold 17 and the portion 19a is in effect hinged at the fold 17. When the collar is being worn, the collar-button is pushed first through one button-hole 20, the corresponding button-hole 15 and then through the other 55

button-hole 20 and the remaining button-hole 15. The outer member 11 is cut in the curved shape usual to turn down collars to provide clearance between it and the inner member 19 for free movement of the tie. The outer member 11 may be of two or more ply and the wing 16 may be of the same ply or less than the remainder of the member.

I claim:

- 10 1. A standing collar comprising inner and outer members of approximately the same length stitched together only at the top edge thereof, each end of the inner member terminating in a tapering portion provided with a button-hole, 15 the ends of the outer member terminating in portions which fold back to form wings, and a locking member at each end of the collar having a portion stitched to each wing in register therewith and having a portion overlapping the inner 20 face of said inner member, said locking member portions having button-holes in register with the inner member button-holes and serving to hold the outer member against the inner member to simulate a standard wing collar.
- 25 2. A standing collar comprising inner and outer members of approximately the same length

stitched together only at the top edge thereof, each end of the inner member terminating in a tapering portion provided with a button-hole and each outer member terminating in a portion which folds back to form a wing, and a locking member attached to each end of the outer member and having a portion overlapping the inner face of the inner member serving to hold the outer member against the inner member to simulate a standard wing collar.

3. A standing collar comprising inner and outer members of approximately the same length stitched together only at the top edge thereof, each end of the inner member terminating in a tapering portion provided with a button-hole, 15 the ends of the outer member terminating in portions which fold back to form wings and a locking member fastened to each end of the outer member adjacent the wing and overlapping the inner face of said inner member, said locking members having button-holes in register with the inner member button holes and said locking member serving to hold the outer member against the inner member to simulate a standard wing collar.

SIMON TOULUMIS.
